UNITED STATES PATENT OFFICE.

FRANK B. ZIEG, OF FREDERICKTOWN, OHIO, ASSIGNOR TO THE F. B. ZIEG MANUFACTURING COMPANY, OF FREDERICKTOWN, OHIO, A CORPORATION OF OHIO.

CULVERT-PIPE.

1,037,709.

Specification of Letters Patent. Patented Sept. 3, 1912.

Application filed April 13, 1912. Serial No. 690,673.

To all whom it may concern:

Be it known that I, FRANK B. ZIEG, a citizen of the United States, residing at Fredericktown, in the county of Knox and 5 State of Ohio, have invented certain new and useful Improvements in Culvert-Pipes, of which the following is a specification.

My invention relates to an improvement in culvert pipes and more particularly to 10 those of the cast iron type.

It is the primary object to provide a pipe of this character made in sections so reinforced that it will have a maximum amount of strength for the amount of metal used in 15 its construction.

Another object is to provide means for fastening the ends of the sections together so that in the construction of a culvert they will not separate.

20 Still another object is to provide means for centering and alining the sections in case the sections are warped or become spread a little in cooling after the cast is made, provision being made to bring the 25 edges to a true circle when the sections are bolted together.

With these and other objects in view, this 30 invention comprises cast sections having means at the ends for interlocking adjacent sections by inserting the ends of one in the bell of the other and giving a slight axial operation to one or both sections, and it further consists in certain novel forms of 35 rectilinear and circular ribbing whereby to give strength to the surface at the points where it would be most exposed and subjected to injury, wear and tear.

In the accompanying drawings—Figure 1 40 is a top plan view of one section. Fig. 2 is an end view. Fig. 3 is an enlarged sectional detail. Fig. 4 is an enlarged top plan view of a portion of the floor section, and Fig. 5 is a sectional view through one of the bulk heads.

45 The two sections may be so designed and constructed that they may both be cast in the same mold and in the preferred form as shown in Fig. 1, the outer surface is formed in longitudinal and transverse raised ribs 1, 1 and 2, 2; and in the uppermost rectangular spaces formed thereby, the circular raised ribs 3, 3 are formed. The purpose of 50 these ribs is to give the pipe additional strength and by providing the pipe with the

straight and circular ribs it is impossible 55 for a wagon wheel or horse's hoof to strike the pipe anywhere without touching the rib, the rib in that way taking the strain and preventing the surface proper of the pipe from being struck or damaged. 60

The two ends of the sections are formed somewhat like the ordinary pipe, that is to say with an enlarged bell at one end and smaller at the other end, the smaller end of one section being adapted to enter the bell 65 end of the other section. The bell end 4 is provided with inwardly projecting lugs 5, 5, and the smaller end is provided with a circumferential rib 6 and with lugs 7, 7 corresponding in shape to the lugs 5, 5 and 70 separated from one another at least the width of a lug so that the lugs and adjacent ends of two pipes, when the latter are put together, interlock and afterward prevent separation by giving a sufficient turn to one 75 or both pipes to bring the lugs of the two opposite or against each other. The adjacent side edges of the pipe sections are formed with a double flange 8, and the object of this is to form a tight joint when the 80 half sections of pipe are bolted together. In this way the bolts draw the half sections close to each other until practically a water tight joint is formed, the bolts passing through the holes in the ears 9, 9. 85

As a provision for truing the sections when warped or spread, the V-shaped rib and corresponding groove 11 and 12 respectively are formed in the outer flange of the double flange so that in putting the sections 90 together and bolting them, if there is any such irregularity due to warping or spreading, it is counteracted in this way and the sections are brought to a true circle and made to fit properly when drawn together. 95 By thus ribbing the surface the strength of the sections is greatly increased and by reason of the interlocking feature at the ends of the sections six or more of the pipe sections may be laid together and by putting a block 100 under each end of the pipe the center will support itself. The advantage of this construction is that when sections of culvert making a length of twenty or thirty feet are placed in the ground and the dirt becomes 105 wedged from beneath the center of the pipe or culvert the same will still support itself and carry any load over the road without

sagging in the center, which is one of the several advantageous features of my present invention.

In order to prevent the dirt from falling over the ends of the pipe when placed across the road, or from washing from beneath the ends of the pipe, I propose to use the flanged bulk heads 13. These are made in half sections adapted to fit the exterior contour of 5 the pipe and be bolted together, they being held in place by the bell at one end and lugs 14, 14 placed at intervals on the surface of the pipe, and the circumferential rib 6 on the other end and lugs 15, 15, corresponding to lugs 14, 14 at the bell end. 10 In this way the bulk heads will necessarily always stand in one position and will be prevented from tipping in either direction without requiring brace rods to support 15 them.

Having fully described my invention, what I claim as new and desire to secure by Letters Patent, is—

1. A culvert pipe having raised annular 25 ribs arranged in pairs on the outer surface adapted to strengthen the pipe and protect its main surface, and longitudinally raised ribs merging into and tangential to said annular ribs.
2. A culvert pipe having raised annular 30 ribs arranged in pairs on the outer surface adapted to strengthen the pipe and protect its main surface, longitudinally raised ribs merging into and tangential to said annular ribs, and transverse ribs intersecting the 35 longitudinal ribs at points between the annular ribs.

3. A culvert pipe made in sections, the contacting edges of which are in the form of a double flange, and means for securing 40 said sections together, the outer portions of said double flanges having ribs and grooves with inclining surfaces adapted to bring the sections together to a true circle when rigidly secured to each other. 45

4. The combination with a pipe having a bell at one end and circumferential rib at the other, and lugs slightly removed therefrom, of sectional or split bulk heads constructed and adapted to fit the space between the bell or rib and be secured together around the pipe. 50

5. A culvert pipe made in longitudinal half-sections, said sections capable of being molded in the same mold and having at their ends uniformly-located lugs extending inwardly and outwardly at opposite ends with spaces therebetween approximately corresponding to the length of the lugs, whereby 55 the end of one pair of sections is adapted to interlock with and by an axial turn be secured to the next adjacent section of culvert.

6. A culvert pipe composed of correspondingly-molded half-sections, each section having uniformly-constructed internal lugs on one end and external lugs on the other end, and means for holding the sections together. 60

In testimony whereof I affix my signature, in the presence of two witnesses.

FRANK B. ZIEG.
